UNITED STATES PATENT OFFICE.

ANDREW H. CANDEE, OF WILKINSBURG, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

1,427,355.

Specification of Letters Patent. Patented Aug. 29, 1922.

Application filed October 13, 1917. Serial No. 196,411.

To all whom it may concern:

Be it known that I, ANDREW H. CANDEE, a citizen of the United States, and a resident of Wilkinsburg, in the county of Allegheny and State of Pennsylvania, have invented 5 a new and useful Improvement in Systems of Control, of which the following is a specification.

My invention relates to systems of control 10 and especially to the remote control of ore-carrying vehicles, or the like, from a tower or station without requiring the presence of an operator upon the vehicles, under normal operating conditions.

One of the objects of my invention is to 15 provide a relatively simple and effective system of the above-indicated character for remotely controlling the acceleration and retardation periods, through a certain operating cycle, of a plurality of electric vehicles which, however, are capable of individual control by an operator, if desired.

Another object of my invention is to provide, in conjunction with a system of the 20 class under consideration, a plurality of safety devices that are connected to the system in a novel manner for preventing certain undesirable conditions, such as overspeeding of the vehicle and false operation 25 of circuits.

A further object of my invention is to provide an interlocking system for the control tower, whereby contiguous track zones or 30 sections are prevented from being oppositely energized, which would result in injury to the rolling stock.

Other minor objects of my invention will 35 become evident from the following detailed description and are set forth with particularity in the appended claims.

My invention may best be understood by 40 reference to the accompanying drawings, wherein Fig. 1 is a diagrammatic view of the main circuits of a system of control embodying the invention; Fig. 2 is a diagrammatic view of the auxiliary circuits that are 45 located upon one vehicle for governing the switching devices corresponding to one of the motors of Fig. 1; Fig. 3 is a detailed diagrammatic view of one of the switches that 50 are employed in the system of Fig. 1; Fig. 4 is a diagrammatic view of the energizing circuits and interlocking arrangement that is

employed in a control tower or station; Fig. 5 is a view, in side elevation, of a portion of 55 the interlocking apparatus that is shown in Fig. 4; and Figs. 6 and 7 are views in perspective illustrating the above-noted interlocking arrangement in detail.

Referring first to the control-tower apparatus (Fig. 4 and Fig. 5), the illustrated system comprises a plurality of operating handles or levers 135, 136 and 137; two ungrounded three-phase supply-circuit conductors 149 and 150; a plurality of independent track zones or sections 151, 152 and 153 severally comprising pairs of third rails T1 and T2 and a plurality of sets of switches 154 to 157, 158 to 161, and 162 to 165, all inclusive, these sets respectively corresponding 60 to track zones 151, 152 and 153. A battery B, or other suitable source of auxiliary energy, is provided for effecting the actuation of the several switches.

It will be understood that one or more 65 control towers or stations will be advantageously located on the railway property, and each track section is governed by a separate interlocking lever of the type indicated, whereby the entire normal vehicle operation 70 may be remotely controlled.

The power system that is employed in connection with my invention is of the three-phase type, the illustrated rails T1 and T2 constituting two of the phase conductors, 75 while a ground return is utilized as the other conductor of the system, as more fully illustrated in Fig. 2. Each operating lever is adapted to occupy the illustrated intermediate position "off" and a plurality of positions respectively marked "Coasting" and "Forward" when the lever is moved in one direction, and "Coasting" and "Reverse" 80 when the lever is actuated in the other direction from the "off" position. The positions "forward" and "reverse" correspond to the interchange of connection between the third rails T1 and T2 and the supply-circuit conductors 149 and 150, such reversal of two phases in a three-phase system serving to 85 effect the reverse rotation of the driven induction motors, as is well understood.

Each interlocking lever comprises a rod or bar 138 which is pivotally mounted at a central point 139 and the lower end of 90 which constitutes a suitable contact tip 140.

100

105

An insulating grip or handle 141 is provided, and an insulating sleeve 141a extends from the grip 141 to the central pivotal point 139. Attached to the upper portion 5 of the insulating sleeve 141a is an arcuate member or strip 142 that is symmetrically disposed with respect to the sleeve 141a and in substantially the same plane, while a pair of arcuate strips 143, of the same radius as 10 the strip 142, but located in a different plane behind the lever rod 138, as clearly shown in Fig. 5, are attached to the opposite ends of the intermediate strip 142. A spring contact clip 144 is located in a position to 15 be engaged by the contact tip 140 when the lever occupies its right-hand "coasting" position, and, when the operating lever is moved to its position "reverse," the contact tip 140 slides over the spring clip 144, which is 20 forced into engagement with a stationary contact terminal 145, whereby the contact tip 140 is electrically connected to both of the contact terminals 144 and 145. Similar contact members 146 and 147 are provided 25 in the remaining positions "coasting" and "forward" of the operating lever. Thus, when the interlocking lever occupies either of its "coasting" positions, only one contact terminal is energized, whereas, in either 30 the "forward" or the "reverse" position, corresponding to full-speed operation of the vehicle, both terminals of the one or the other pair, corresponding to forward or reverse operation, are energized.

35 As previously mentioned, the opposite energization of contiguous track zones should be prevented in order to obviate current surges and mechanical difficulties in the vehicle motors by reason of sudden reversal thereof. The purpose of the illustrated interlocking arrangement for which, of course, any other equivalent structure may be substituted within the spirit of my invention, is to insure that an intermediate 40 dead or de-energized track zone or section is interposed between two zones that are oppositely energized, for example, in connection with switching or shunting of vehicles when not being employed in their regular 45 run or cycle of operation.

50

It will be observed that the illustrated interlocking levers may all be thrown to either the "forward" or the "reverse" position without mutual interference, but, if, 55 under such conditions, when the lever 137 occupies its "forward" position, for example, (see Fig. 7) it is attempted to throw the lever 136 to its "reverse" position, such action is prevented by the mechanical interlocking of the arcuate strips 143 of the respective levers as soon as the lever 136 is moved to its intermediate or "off" position. However, if the lever 136 occupies such intermediate position, it is then possible to 65 actuate the third lever 135 to its "reverse"

position. In this way, the track zones 151 and 153 may be oppositely energized, with a dead section 152 between them, but it is impossible to oppositely energize any two contiguous sections.

70 On the other hand, if the interlocking lever 137 is assumed as occupying its "reverse" position, (see Fig. 6) then movement of the succeeding lever 136 beyond its "off" position in a forward direction is prevented by the mechanical engagement of the arcuate strips 142, and again track zones 151 and 153 may be oppositely energized by manipulation of the corresponding levers 137 and 135 only when the intermediate 75 lever 136 occupies its "off" position. By providing an equivalent interlocking arrangement between contiguous pairs of the entire complement of interlocking levers in the control tower or station, the opposite 80 energization of any two contiguous track zones or sections is effectively prevented.

85 Referring now to Fig. 1, illustrating the complete main-circuit connections for one driving induction motor of a vehicle and 90 partial connections for the second driving motor that is preferably provided, the system shown comprises the third rails T1 and T2 and the ground return, whereby a three-phase source of power is available; a main 95 driving motor 1 of the familiar induction type comprising a delta-connected primary or stator winding P1 and a wound rotor S1; a plurality of variable resistors 2, 3 and 4 and co-operating switches R1 to R6, inclusive, for varying the secondary-circuit resistance of the induction motor to govern the operation thereof, in accordance with familiar principles; a plurality of limit 100 switches L1 and L2 for automatically governing the operation of the system; a plurality of current relays 5 and 6, severally having two contact disks, and current relays 7 and 8, each provided with a single contact disk, 105 for governing certain auxiliary-circuit connections to be set forth; and a plurality of electrically-controlled switches 10 to 13, inclusive, which are employed in pairs to effect forward or reverse operation of the induction motor 1 when controlled from the 110 individual vehicle, irrespective of the relative energization of the third rails T1 and T2.

115 To provide the desired ground return for the motor system, the grounded running rails 15 are connected, through the trucks or sets of wheels 16, to a conductor 17 that is permanently connected to one terminal of the primary induction-motor winding P1.

120 Each vehicle is provided with a plurality of third-rail shoes 18 and 19 for respectively engaging the third rails T1 and T2, and conductors 20 and 21 are respectively connected to the shoes 18 and 19 for supplying energy to the remaining terminals of the 125 130

primary induction-motor winding, dependent upon the particular set of direction-controlling switches 10 and 13, or 11 and 12, that is employed.

5 The current relays 5 and 7 have their actuating coils respectively connected in series relation with the supply conductors 21 and 20 to be energized by the current traversing the primary winding of the illustrated induction motor, while a similar pair of current relays 6 and 8 have their actuating coils connected in the primary circuits that correspond to the third rails T1 and T2 of the second driving induction motor (not shown) 10 for which the conductors 23, 24 and 25, respectively corresponding to Ground, third-rail shoe 18 and third-rail shoe 19, are provided.

The current relays 7 and 8 have a relatively 20 high setting and are provided with a single contact disk or bridging contact member for closing certain auxiliary circuits, to be described, when the relays occupy the illustrated lower positions. The current relays 25 5 and 6, however, are of a similar double-disk type, the relay 5 being shown as comprising two disks or bridging contact members 26 and 27 which are loosely mounted upon the stem of the current relay and are 30 biased, by an intermediate coil spring 28, towards engagement with a corresponding nut or stop member 29. Thus, in the illustrated normal position of the relay 5, the lower contact disk 27 closes a certain auxiliary 35 circuit while the upper disk 26 is prevented, by the allied nut 29, from engaging an upper pair of stationary contact members. Upon energization of the relay to a certain value, which is lower than the setting of 40 the single-disk current relays 7 and 8, the upper contact disk 26 engages the upper stationary contact members before the spring 28 permits the lower contact disk 27 to become disengaged from the corresponding 45 stationary contact members. A similar action occurs when the current relay 5 drops to its lower position, and, in this way, whenever auxiliary circuit is closed by the current relays 5 or 6 is maintained until the 50 other auxiliary circuit has been energized by the relay movement, thus preventing an open-circuit of the auxiliary connections.

The limit switches L2 and L1 are adapted to control certain auxiliary circuits in accordance with relatively light and relatively heavy main-current conditions, respectively, although, by reason of the peculiar location of the two limit switches, such action is secured by the use of identical limit switches 60 and without any variation in the setting thereof.

In the present system, it is desired to manipulate the secondary-circuit resistors of the driving induction motors in accordance with the load condition of the vehicle;

that is, when the vehicle is carrying a capacity load it is desired to vary the secondary-circuit resistance to automatically maintain a relatively heavy draft of motor current through the agency of the limit switch L1, 70 while, under light-load conditions, when the vehicle is empty, it is desired to vary the motor operation in accordance with relatively light-current conditions, as governed by the limit switch L2. Since the limit 75 switch L1 is connected in the conductor 23 for the second driving motor and receives only single-motor current, whereas the limit switch L2 is connected in the common ground-circuit conductor 17 to receive two-motor current, it follows that the desired 80 governing of motor circuits, in accordance with the load condition of the vehicle, may be effected by the two limit switches. The peculiar auxiliary-circuit arrangement of the 85 contact members of the two limit switches to permit of the desired automatic operation of the driving motors will be set forth in detail in connection with Fig. 2.

Reference may now be had to Fig. 2, 90 wherein the system shown comprises the polyphase supply-circuit conductors T1, T2 and Ground; the auxiliary contact members of the current relays 5, 6, 7 and 8; a brake relay 30 and a centrifugal switch 31 for 95 governing the operation of an air-brake valve 32; the actuating coils of the several switches that are shown in Fig. 1; together with a plurality of electrical interlocks of the familiar type that is shown in Fig. 3; a change-over switch CO for varying certain auxiliary-circuit connections in accordance with the vehicle load; a master controller MC that is adapted to occupy a plurality of positions corresponding to both forward 100 and reverse operation of the vehicle motors; and a control transformer CT for supplying energy from the third rails to the auxiliary 105 circuits.

The brake relay 30 comprises a double-core movable element having a plurality of cumulatively-related actuating coils 34 and 35 that are respectively energized from the third rails T1 and T2, and a plurality of bridging contact members 36, 37 and 38. 110

The centrifugal switch 31 may be of any familiar type for actuating a movable member, under predetermined speed conditions of the vehicle and is here shown as comprising a mechanism 40 of the well-known fly-ball type, which is connected, through a suitable transmission mechanism 41, to the truck-axle 16. A movable switch rod 42 is pivotally associated with the fly-ball mechanism 40, being normally biased to the illustrated upper position, wherein a plurality of bridging contact members 44, 45 and 46 close certain auxiliary circuits to be described. The contact disk 44 is rigidly secured to the rod 42, whereby its circuit is 120 125 130

established only while the vehicle is at rest. On the contrary, the contact disks 45 and 46 are loosely mounted upon the rod 42 and maintain their circuit connections, except in 5 the event of over-speed conditions of the vehicle, as hereinafter more fully set forth, through the agency of suitable coil springs 43 and 43a.

A latching member 47 is biased, through 10 the action of a compression spring 48, into engagement with a co-operating block or notched member 49 that is secured to the switch rod 42, the latching member 47 being normally disengaged from the block 49 15 but being adapted to maintain the switch rod in its lower or circuit-opening position, in opposition to the biasing action of the fly-ball mechanism 40, after the vehicle speed has reached a value sufficiently high 20 to throw the fly-ball device into such a position that the switch rod 42 is actuated to a complete open-circuit position to permit the locking engagement of the latching member 47 and the co-operating block 49.

25 The air-brake valve 32 may be of any familiar type and is shown as comprising a shell or encasing member 50 having an inlet or supply pipe 51 and an outlet or delivery pipe 52 between which is interposed a suitable plug-valve member 53 to which is secured a double core member 54 that is provided with a plurality of cumulatively-related actuating coils 55 and 56.

The purpose of the air-brake valve 32 is 35 to admit fluid pressure to the familiar vehicle brake-cylinder (not shown) except when the one or the other of the actuating coils 55 and 56 is energized in accordance with circuits to be traced, whereby the air-brakes are maintained inoperative during 40 normal running or coasting conditions of the vehicle motors.

The control transformer CT is employed 45 for the purpose of preventing certain false operations or energizations of the auxiliary circuits, which would occur if an uninterrupted metallic circuit from the third rails T1 and T2 through the master controller to the various switch-actuating coils were 50 employed. However, by interposing the control transformer CT between the third rails and the switch-actuating coils, the formation of undesirable or false connections or energizations during the operation of the 55 vehicle is effectively prevented.

The change-over switch CO may be of 60 any suitable two-position or double-throw type and is shown in a diagrammatic manner as adapted to occupy two positions *h* and *l*, respectively corresponding to heavy load and light load of the vehicle, or, in the case of ore-carrying cars, for example, respectively corresponding to full and to empty condition. In conjunction with the

change-over switch, the limit switches L1 65 and L2 are employed to properly accelerate the vehicles in accordance with the load conditions thereof, as previously explained.

It will be understood that any suitable method for actuating the change-over 70 switch to the one or the other of its operative positions may be employed, for example, ordinary manual operation or actuation by suitable track ramps that are located at proper points along the road-bed. 75

As previously stated, the vehicles are normally started and stopped from the control tower or station, and the master controller MC upon each vehicle is employed only in special instances where individual control 80 is desired. Normally, the master controller occupies its illustrated "full-speed" position corresponding to forward operation.

Assuming that the interlocking switches in the control tower have been manipulated 85 to energize the third rails T1 and T2 so that the three-phase supply circuit is in operative condition corresponding to forward operation, the opposite terminals of the primary winding 57 of the control transformer 90 are connected through conductor 20 and rail-shoe 18 to the third rail T1 and through conductor 21 and rail-shoe 19 to the other third rail T2, respectively.

An electromotive force is thus produced in 95 the secondary winding 58 of the control transformer, a circuit being established from one terminal thereof through bridging contact members 61 and 62 of the single-disk current relays 8 and 7, respectively, conductor 63, lower contact members 64 and 27 of the current relays 6 and 5, respectively, conductor 66 and control finger 67 to a contact segment 68 of the master controller. One circuit is continued from the contact segment 68 through control finger 69, conductors 70 and 71, interlock 11-out, actuating coil of the switch 13 and conductors 72 and 73 to the opposite terminal of the secondary transformer winding 58. Upon the closure 110 of switch 13, another circuit is completed from the conductor 71, through conductor 74, interlocks 13-in and 12-out and the actuating coil of the switch 10 to the terminal conductor 72.

115 By reference to Fig. 1, it will be observed that the closure of the switches 13 and 10 connects two of the terminals of the primary induction motor winding P1 to the third-rail shoes T1 and T2, and, since the remaining motor terminal is permanently connected to Ground, the induction motor is set in operation in the direction to be considered as "forward," all of the secondary-circuit resistors 2, 3 and 4 being actively 120 connected in circuit by the closure of switch R1, in a manner about to be described. It 125 will be understood that the remaining ve-

hicle motor is preferably controlled in a similar manner.

The traversal of current through the stator windings of the two induction motors first causes the current relays 5 and 6 and, subsequently, the current relays 7 and 8 to be moved to the upper positions, whereby the upper terminal of the secondary winding 58 of the control transformer CT is connected to the conductor 66 through conductor 75 and the upper contact members 76 and 26 of the current relays 6 and 5, respectively. As previously explained, the peculiar construction of the current relays 5 and 6 causes the upper set of circuits to be closed before the lower set is opened, and, consequently, an uninterrupted flow of current energy through the circuit just traced is maintained. The further functions of the current relays 5 to 8, inclusive, will be hereinafter described in connection with the regenerative operation of the driving motors and other similar conditions entailing a substantial interruption of supply-circuit energy in the control system.

Assuming that the vehicles to be controlled are heavily loaded and that the change-over switch CO consequently occupies its position *h*, another auxiliary circuit is continued from the conductor 70 through interlock 13-in, conductor 81, movable contact member 82 of the change-over switch CO, in its position *h*, conductor 83, directly to the actuating coil for the switch R1, and thence to the terminal conductor 73. The switch R1 is thus closed to connect the entire secondary-circuit resistors 2, 3 and 4 in active circuit relation with the secondary motor winding S1.

Since the change-over switch CO occupies its heavy-load position *h*, a further auxiliary circuit is continued from the master controller contact segment 68 through control finger 91, conductor 92, interlock 10-in, movable contact member 93 of the change-over switch, bridging contact member 94 of the single-motor current limit switch L1, when occupying its lower position, conductor 95, interlock 96-R1-in, conductor 97, interlock 98-R2-out and thence, through the actuating coil for the switch R2, to the terminal conductor 73. As soon as the switch R2 is closed, a holding circuit for its actuating coil is completed from the lower terminal thereof through interlock 98-R2-in and conductors 99, 100 and 101, to the above-mentioned interlock 10-in, which is positively energized whenever the master controller occupies its illustrated position.

As previously explained, the limit switch L2 carries the total current of both driving motors, whereas the limit switch L1 is energized in accordance with the current of only one of such motors. Consequently, under

heavy-load conditions of the vehicle, the limit switch L2 is maintained in its upper position, and the automatic control of the several resistor short-circuiting switches is dependent upon the single-motor-current limit switch L1 alone. Thus, when the limit switch L1 again drops to its lower position, after the closure of the short-circuiting switch R2, an auxiliary circuit is continued from the conductor 97 through interlock 102-R2-in and thence to the actuating coil for the switch R3. In this way, the remaining resistor-short-circuiting switches are progressively closed in accordance with the movements of the limit switch L1, as will be understood. The vehicle motors are thus automatically accelerated to full-speed operation and are maintained in such condition so long as the third rails T1 and T2 are not de-energized or reversed in polarity.

Assuming that the vehicle motors have been de-energized and stopped, as subsequently explained, and that the load of ore or coal that the vehicle has been carrying is removed, in accordance with any well-known practice, so that the vehicle is running under light-load conditions, the change-over switch CO is thrown to its corresponding position *l*, in the previously-mentioned manner, and, upon re-energization of the third rails T1 and T2, the switches 13 and 10 are again closed. However a new circuit for the actuating coil of the switch R1 is completed from the master-controller contact segment 68 through control finger 91, conductor 92 and interlock 10-in to conductor 101, whence circuit is complete through contact disk 85 of the total-motor-current-limit switch L2 to interlock 84-R1-out and the actuating coil for the switch R1. The single-motor-current-limit switch L2 is inoperative under light-load conditions of the vehicle, since the change-over switch CO occupies its position *l* to interrupt the connection of the contact disk 94 of the limit switch L1 to conductor 101.

The remaining resistor-short-circuiting switches are progressively closed in accordance with the movements of the limit switch L2, whereby a relatively light current is automatically maintained in the stator winding of the induction motors to effect proper acceleration under the light-load conditions of the vehicle.

The normally operative auxiliary brake circuits may be traced as follows:

One such circuit is established from the third-rail shoe 19 through conductors 21 and 103, control fingers 104 and 105, which are bridged by contact segment 106 of the master controller, conductor 107, junction-point 108, conductor 109, actuating coil 35 of the brake relay 30, conductor 110, bridging contact member 44 of the centrifugal switch

31, in its stationary or normal position, and conductors 111 and 112 to the Ground.

The brake relay 30 is thus actuated to its upper or circuit-closing position, whereupon 5 a "holding" circuit, including contact disk 36 of the brake relay, is utilized to directly connect the conductors 110 and 112, thus rendering the energization of the relay independent of the position of the centrifugal 10 switch 31, which interrupts the circuit through its contact disk 44 whenever the vehicle is in motion.

A new circuit is completed from the junction-point 108 through conductor 113, contact disk 37 of the brake relay, conductor 114, contact disk 45 of the centrifugal switch, conductor 115, actuating coil 55 for the air-brake valve 32 and conductor 116 to Ground. The valve 32 is thus closed to prevent 15 access of fluid pressure to the brake-cylinder pipe 52, and, consequently, the air-brakes are maintained inoperative whenever the actuating coil 55 is energized.

A duplicate set of circuits is established 20 from the third-rail shoe 18 through conductor 20, control fingers 117 and 118, which are bridged by contact segment 119 of the master controller, conductor 120, actuating coil 34 for the brake relay 30 and thence, 25 through conductor 110, to Ground, as already traced. A further circuit is completed, when the brake relay occupies its upper position, from the conductor 120 through contact disk 38 of the brake relay, conductor 123, contact disk 46 of the centrifugal switch 30 35 31, conductor 124 and the actuating coil 56 for the air-brake valve 32 to the conductor 116.

In this way, the brake relay 30 and the 40 air-brake valve 32 are maintained in their upper or energized positions whenever either one of the third rails T1 and T2 is energized, and the master controller MC concurrently occupies any position except the 45 intermediate position marked "Brake."

The necessity for the duplicate set of auxiliary brake circuits will be evident from the fact that either of the third rails T1 and T2 may be de-energized to produce coasting 50 conditions of the driving motors, dependent upon the particular "coasting" positions occupied by the interlocking switches that are shown in Fig. 4. As previously described, the actuation of the interlocking device 135, 55 for example, to either of its "coasting" positions de-energizes the one or the other third rail T1 or T2 and thus de-energizes one of the main-circuit conductors for the primary induction motor windings P1. Consequently, the control transformer CT (Fig. 2) is 60 de-energized, and the previously-traced auxiliary circuits are all likewise de-energized to disconnect the primary motor windings from the supply circuit by opening the sets of 65 switches 13 and 10 or 12 and 11, dependent

upon the direction of operation of the motors.

In this way, the vehicles are permitted to coast by de-energizing one of the third rails T1 and T2, although the one or the other of the duplicate auxiliary brake circuits is maintained energized to thus prevent the operation of the air-brakes when it is desired to effect coasting operation of the vehicle. 70

To stop the vehicle, the corresponding interlocking switch 135 or the like is thrown to its "off" position, whereby the remaining third rail is de-energized to thus permit the brake relay 30 and the air-brake valve 32 to assume their illustrated lower positions to 75 thereby permit fluid pressure to enter the brake-cylinder to apply the vehicle air-brakes and rapidly arrest the vehicle movement. The air-brakes remain applied until the one or the other of the third rails T1 80 and T2 is again energized by movement of the corresponding interlocking lever to an operative position.

During such coasting and braking conditions, the control transformer CT, in conjunction with the several current relays 5 to 8, inclusive, functions to prevent false operation by undesirable circuit energizations. When one third rail is de-energized from the control tower to effect vehicle 85 coasting, a three-phase regenerative circuit tends to be maintained by reason of the fact that the other two phase-conductors are still energized, and the momentum-driven machine attempts to re-energize the dead third-rail. Even when both rails are de-energized, the motors tend to maintain voltage for a very short interval. This inherent action also tends to energize the control 90 transformer and maintain the direction-controlling switches 10 and 13 in their closed positions. However, such tendency is counteracted in the following manner by the current relays 5 to 8, inclusive. If third-rail T1 is de-energized, current relays 6 and 7 100 drop, thus completely opening the auxiliary circuit and causing the desired opening of the motor-governing switches. On the other hand, de-energizing third-rail T2 drops relays 5 to 8 and opens the switches 110 in the same way.

The arrangement of the current relays 5 to 8, inclusive, is also adapted to prevent an interruption of the main circuits upon a transition of machine operation from acceleration to regeneration. Such transition, as is well known, inherently occurs in an induction motor whenever the speed tends to exceed the synchronous value. Under such conditions, the current in each main machine will pass through a minimum value to attain the necessarily reversed flow of the regenerated current. As the operating range of the relays cannot always be adapted to hold them closed at such minimum 120 125 130

value, the connections shown allow the relays to drop during this transition period without opening the main circuits. The single-disk or heavy-current relays 7 and 8 thus first drop to their lower position, and subsequently, one or both of the double-disk or light-current relays 5 and 6 drop to the illustrated lower position, although the upper circuits are maintained until the lower circuits are closed, as previously explained.

In this way, the auxiliary circuits remain energized to prevent interruption of the motor circuits, and, as soon as the regenerative current assumes a normal value, the various relays again assume their upper positions without, however, opening the auxiliary circuits. Thus, transition from acceleration to regeneration, or vice versa, may occur at any time without modifying the vehicle operation, practically speaking.

If, at any time under full-speed or coasting conditions, the vehicle speed exceeds a predetermined critical value, the centrifugal switch 31 operates to open the auxiliary circuits including contact disks 45 and 46, to de-energize both actuating coils for the air-brake valve 32 and thus apply the vehicle brakes to bring the car to a standstill. As previously explained, when the centrifugal switch 31 is actuated to its emergency position, the latching device 47 locks with the notched block 49 to maintain the switch in its open position until the latching member 47 is manually actuated to permit the spring 48 to return the centrifugal switch to its illustrated position.

The present system automatically functions to prevent sudden reversal of motor operation which, as is well known, is undesirable, for both electrical and mechanical reasons. Whenever the corresponding interlocking lever of Fig. 4 is actuated from its "forward" to its "reverse" position, the third rails T1 and T2 are temporarily de-energized as the lever passes through its position "off" and the vehicle brakes are thus applied to arrest the movement of the vehicle, which cannot be again set in operation until after a complete standstill has been effected. This result is attained by reason of the fact that the previously-traced circuit for the actuating coils of the brake relay 30 is interrupted by bridging contact member 44 of the centrifugal switch 31 whenever the vehicle is in motion, and, since the holding circuit, including contact disk 36 of the brake relay, is also interrupted when the relay drops to its lower position upon the temporary de-energization of the third rails T1 and T2, it follows that the brake relay cannot be raised to its operative position to release the air-brakes until the vehicle has come to rest, as evidenced by the occupation of its uppermost position by

the contact disk 44 of the centrifugal switch.

If it is desired, for switching or other purposes, to control any one vehicle independently of the others during the period of energization of both the third-rail conductors T1 and T2, the corresponding master controller MC may be manually actuated to its position marked "Switching", whereby control finger 91 becomes disengaged from the contact segment 68, and, consequently, the driving induction motors will operate at a relatively low speed by reason of the high value of resistance that is thereby included in the secondary circuits thereof. In this way, switching operations, for example, may be readily accomplished at a desirably reduced speed.

By manually actuating the master controller MC to its position marked "Coast", the actuating coils for the main-circuit switches are de-energized to disconnect the motors from the supply circuit, but, inasmuch as the actuating coils for the air-brake valve 32 remain energized in such "coast" position of the master controller, the air-brakes are not applied, and, consequently, the vehicle is permitted to coast at a speed dependent upon its own momentum.

However, to manually effect braking of the vehicle, the master controller is moved to its middle position marked "Brake", whereupon the actuating coils for the air-brake valves 32 are de-energized to permit application of the mechanical brakes and bring the vehicle to a standstill.

The above-mentioned provision of preventing reversed operation of the driving motors until after the vehicle has been stopped, is rendered inoperative whenever the master controller MC occupies any position other than the full-speed positions corresponding to either forward or reverse operation, since immediate reversal, under such reduced speed conditions, will work no injury to the apparatus. The function just recited is made possible by reason of a new return circuit that is established from the lower terminals of the actuating coils 34 and 35 for the brake relay 30 through conductor 125, control fingers 126 and 127, 115 which are bridged by contact segment 128 of the master controller in any of the above-mentioned positions, and conductors 129 and 112 to Ground. The brake relay is thus maintained in its upper or operative position to prevent application of the air-brakes irrespective of the concurrent position of the centrifugal switch 31, except that the previously-mentioned over-speed protection is available at all times.

In the "full-speed-reverse" position of the master controller, the control finger 91 re-engages the contact segment 68, while a new control finger 131 is substituted for the previously-mentioned control finger 69, circuit 130

being completed from the finger 131 through conductors 132 and 133, interlock 10-out and the actuating coil of the switch 12 to the negative conductor 72. Another circuit 5 is thereupon completed from conductor 133 through conductor 134, interlock 12-in and 13-out and the actuating coil of the switch 11 to the negative conductor. In this way, the two ungrounded terminals of the primary 10 motor windings are connected to the opposite third rails from those utilized during the forward operation, whereby the driving motor rotational direction is reversed, in accordance with familiar principles.

"Switching" and "coast" positions are again preferably provided during reversed operation of the vehicle, and perform functions similar to those hereinbefore set forth 20 in connection with the corresponding positions in the other portion of the master controller. The remaining operation of the system during reversed rotation of the main motors is identical with that previously described, and no further description thereof is deemed necessary.

I do not wish to be restricted to the specific circuit connections, structural details or arrangement of parts herein set forth, as 30 various modifications thereof may be effected without departing from the spirit and scope of my invention. I desire, therefore, that only such limitations shall be imposed as are indicated in the appended claims.

35 I claim as my invention:

1. In a system of control, the combination with a plurality of independent distribution-circuit sections, of a plurality of switching devices corresponding to the respective 40 sections for reversing the polarity thereof individually, and means for preventing the relative reversal of polarity of predetermined sets of sections.

2. In a system of vehicle control, the combination with a supply circuit and a plurality of independent distribution-circuit sections adapted to be energized therefrom, of a plurality of switching devices corresponding to the respective sections for reversing the individual connection thereof to the supply circuit, a plurality of control 55 means for governing said switching devices, and interlocking means associated with said control means for preventing the relative reversal of polarity of contiguous sections.

3. In a system of vehicle control, the combination with a supply circuit and a plurality of independent distribution-circuit sections adapted to be energized therefrom, 60 of a plurality of switching devices corresponding to the respective sections for reversing the individual connection thereof to the supply circuit, a plurality of control means for governing said switching devices, 65 and interlocking means associated with said

control means for insuring that two sections having relatively reversed polarity be separated by a de-energized section.

4. In a system of vehicle control, the combination with a two-conductor supply circuit and a plurality of independent two-conductor distribution circuit sections adapted to be energized therefrom, of a plurality of sets of switching devices corresponding to the respective sections for reversing the individual connection thereof to the supply circuit, a plurality of multi-position control levers for manipulating said switching devices, and interlocking members operated by said control levers for insuring that two sections having relatively reversed polarity be separated by a de-energized section.

5. In a system of vehicle control, the combination with a supply circuit, of a plural-conductor distribution-circuit, and an electric vehicle operatively connected thereto and adapted to "run", "coast" or "brake", according to the number of energized conductors in said distribution circuit.

6. In a system of vehicle control, the combination with a supply circuit, of a plural-conductor distribution-circuit, an electric vehicle embodying a motor-control system operatively connected to said distribution circuit, and remote-control means for energizing all, a portion, and none, of the distribution-circuit conductors, said motor-control system being so organized that the vehicle is thereby caused to "run", "coast" and "brake", respectively.

7. In a system of vehicle control, the combination with a supply circuit, of a plural-conductor distribution-circuit, an electric vehicle operatively connected thereto and adapted to "run", "coast" or "brake", according to the number of energized conductors in said distribution circuit, and means for governing the vehicle independently of said distribution circuit, under predetermined conditions.

8. In a system of vehicle control, the combination with a supply circuit, of a plural-conductor distribution-circuit, an electric vehicle embodying a motor-control system operatively connected to said distribution circuit, remote-control means for energizing all, a portion, and none, of the distribution-circuit conductors, said motor-control system being so organized that the vehicle is thereby caused to "run", "coast" and "brake", respectively, and control means located on the vehicle for independently governing the operation thereof during periods of complete energization of said distribution-circuit.

9. In a system of vehicle control, the combination with a supply circuit, of a plural-conductor distribution-circuit, an electric vehicle embodying a motor-control system operatively connected to said distribution

- circuit, and remote-control means for energizing various numbers of the distribution-circuit conductors, said motor-control system including means for effecting "running" 5 of the vehicle when said conductors are all energized and for effecting "coasting" when only one of said conductors is energized, and including braking means that is rendered operative only when said distribution circuit 10 is completely de-energized.
10. In a system of control, the combination with a plurality of motors for driving a common vehicle, of a plurality of relay devices, respectively having actuating coils energized by a portion, and by all, of the currents traversing said motors, for automatically governing the operation thereof independently in accordance with the load conditions of the vehicles. 15
- 20 11. In a system of control, the combination with a plurality of motors for driving a common vehicle, of a plurality of identical relay devices, respectively having actuating coils energized by all and by one of the currents traversing said motors, for automatically governing the operation thereof under light-load and heavy-load conditions, respectively, of the vehicle.
12. In a system of control, the combination with a plurality of motors for driving a common vehicle, of a plurality of relay devices, respectively having actuating coils energized by one and by all of the currents traversing said motors, and a change-over 30 switch having positions corresponding to materially different load conditions of the vehicle for permitting automatic operation of the control system independently by the different relay devices under said different 35 load conditions.
13. In a system of control, the combination with a plurality of wound-rotor induction motors for driving a common vehicle, of a plurality of identical limit switches respectively having actuating coils energized by one and by both of the motor primary 45 currents and having auxiliary-circuit contact members connected in parallel relation, a change-over switch having positions corresponding to light-load and heavy-load 50 conditions of the vehicle, a variable-resistance regulating circuit for each wound rotor, and auxiliary-circuit connections associated with said change-over switch for automatically 55 governing said regulating circuit by the single-motor-current-energized limit switch and by the other limit switch under said heavy-load and light-load conditions of the vehicle, respectively, said change-over switch 60 open-circuiting the contact members of the single-motor-current-energized limit switch under said light-load conditions.
14. In a system of control, the combination with a dynamo-electric machine, of means 65 for reversing the direction of rotation there- of, and speed-responsive means for preventing such reversal.
15. In a system of control, the combination with a dynamo-electric machine, of means for reversing the direction of rotation thereof, and speed-responsive means for preventing such reversal until the machine is at rest. 70
16. In a system of control, the combination with a dynamo-electric machine, of a controller for reversing certain circuit energizations of said machine, and centrifugally-controlled means for rendering said reversal inoperative except under substantially stationary conditions of the machine. 75
17. In a system of control, the combination with a dynamo-electric machine, of a plural-position controller having positions corresponding to "forward" and "reverse" full-speed operation, independent control means for reversing the energization of certain machine circuits, means for preventing actual machine reversal until the machine is at rest when said controller occupies either "full-speed" position, and means associated with said controller for rendering said preventing means inoperative when said controller occupies positions other than said "full-speed" positions. 80
18. In a system of control, the combination with an alternating-current supply circuit and a dynamo-electric machine, of a distribution circuit adapted to be connected to said machine, an auxiliary governing system for said machine, independent means for controlling and reversing the energization of said distribution-circuit from said supply circuit, and an auxiliary transformer having one winding connected across said distribution circuit for inductively supplying energy to said auxiliary system. 85
19. In a system of vehicle control, the combination with a dynamo-electric machine, and a switching device normally dependent for closure upon the continuous energization of said machine, of means operative upon a transition from acceleration to regeneration, or vice versa, for maintaining said switching device closed during the concurrent change of current conditions. 95
20. In a system of vehicle control, the combination with a polyphase supply circuit and an induction motor driven therefrom, of an auxiliary governing system for the motor energized from said supply circuit, and a plurality of current relays operative upon a transition from acceleration to regeneration, or vice versa, for maintaining the auxiliary system energized during the concurrent reversal of current conditions. 100
21. In a system of vehicle control, the combination with a supply circuit, of a plural-conductor distribution circuit, an induction motor, an auxiliary governing system energized from said distribution circuit and including switches for connecting said motor 115
- 120
- 125
- 130

thereto, means for de-energizing one of said distribution-circuit conductors to effect motor-coasting conditions, and means for insuring the opening of said switches under such 5 coasting conditions.

22. In a system of vehicle control, the combination with a three-phase supply circuit, of a distribution circuit including two conductors, an induction motor, an auxiliary 10 governing system energized from said conductors and including switches for connecting said motor thereto, means for de-energizing the one or the other of said conductors to effect motor-coasting conditions, and relay means for insuring the de-energization 15 of said auxiliary system under such coasting conditions irrespective of the tendency of the induction motor to maintain a three-phase energization.

23. In a system of vehicle control, the combination with a three-phase supply circuit,

of a distribution circuit including two conductors, an induction motor, an auxiliary governing system energized from said conductors and including switches for connecting 25 said motor thereto, means for de-energizing the one or the other of said conductors to effect motor-coasting conditions, and a plurality of sets of different relay devices energized from each conductor, one relay of 30 each set being adapted, under conditions of normal motor operation, to maintain the energization of said auxiliary system and said relays being adapted, under said coasting conditions, to insure the de-energization of 35 said auxiliary system irrespective of the particular one of said conductors that is de-energized.

In testimony whereof, I have hereunto subscribed my name this 4th day of Oct., 40

ANDREW H. CANDEE.
